UNITED STATES PATENT OFFICE.

GEORGE P. BARKER AND OLIVER E. UNDERWOOD, OF INDIANAPOLIS, INDIANA.

SAFETY APPARATUS FOR ELEVATORS.

1,351,827.

Specification of Letters Patent. Patented Sept. 7, 1920.

Application filed October 3, 1919. Serial No. 328,148.

To all whom it may concern:

Be it known that we, GEORGE P. BARKER and OLIVER E. UNDERWOOD, citizens of the United States, residing at Indianapolis, in 5 the county of Marion and State of Indiana, have invented certain new and useful Improvements in Safety Apparatus for Elevators, of which the following is a specification, reference being had therein to the 10 accompanying drawings.

This invention relates to a safety apparatus for elevators, and has for its object the provision of simple and efficient means that will operate for stopping an elevator 15 cage when it descends too fast, or when the elevator cage is accidentally lowered by the breaking of some lifting part or the like.

With this and other objects in view, our 20 invention comprises certain novel constructions, combinations, and arrangements of parts as will be hereinafter specifically described, illustrated in the accompanying drawings, and more particularly pointed out 25 in the appended claims.

In the drawings,

Figure 1 is a top plan view of the floor of an elevator car or cage, showing a rail associated therewith, and my safety apparatus 30 on the floor and operably associated with the rail.

Fig. 2 is a sectional view taken on line 2—2, Fig. 1.

Fig. 3 is a view in elevation of the structure shown in Fig. 1.

Fig. 4 is a diagram of the electric wiring.

Fig. 5 is a bottom plan view of the floor of the elevator car or cage, showing the clutch mechanism for gripping the auxiliary rails, while

Fig. 6 is a sectional view taken on line 6—6, Fig. 5.

Referring to the drawings by numerals, 1 designates the floor of the car or cage, and 45 2 the back thereof. The back 2 is provided with a journal 3, in which is journaled shaft 4. On the outer end of shaft 4 is secured roller 5 that travels against the side of primary rail 6. On the inner end of 50 shaft 4 is secured a beveled gear 7 that meshes with the beveled gear 8 of the governor 9.

A sleeve 10 is fastened by means of nut 11 upon the floor 1; the lower reduced end 55 of the sleeve 10 extends through the floor (Fig. 2), whereas the comparatively long

reduced upper end 10^a carries the sliding gear 8 as well as the vertical sliding cap 12. Extending through the entire sleeve 10, including its reduced end portions, is a rod 60 13, to the upper end of which rod is fixedly secured the cap 12. Spring arms 14, carrying adjustable weights 15, are attached at their upper ends to the outer surface of cap 12, and at their lower ends to the sliding gear 8 (Fig. 2).

Terminal posts 16 are secured to the under face of the floor 1, carrying short blade 17 and long blade 18, which blades overlap at their ends; while the blades are engaging 70 as shown in Fig. 3, a circuit will be closed therethrough for the purpose hereinafter specified.

The roller 5 travels against the side of the rail 6, and should, for any reason, the 75 car travel faster than desired, owing to the regulation by the operator, of governor 9, the governor will be operated through the roller 5, shaft 4, and meshing gears 7 and 8, to cause cap 12 to be drawn down on the 80 reduced upper end 10^a of the sleeve 10, securely forcing rod 13 down within the sleeve, causing the lower end of the rod to force the long blade 18 downward, breaking the circuit as shown in Fig. 4. The breaking 85 of the circuit will deenergize the magnet 19 carried by bracket 20, which bracket 20 has pivoted, at 21, arm 22, which arm 22 carries at its upper end a large weight 23. Upon the magnet 19 being deenergized, this 90 will cause the weight 23 to be released and dropped to the position shown by dotted lines 24 (Fig. 3), the weight striking the head 25 on the horizontal angle arm 26 of the switch blade 27 (Fig. 3). The switch 95 blade 27 is pivotally mounted at 28, and normally is held between the spring lips 29 of the switch 30. A grip 31 is fastened to the upper end of blade 27. Upon the weight 23 striking the head 25, the blade 100 27 will be withdrawn from between the lips 29, breaking the circuit through switch 30, consequently breaking the circuit in the solenoids 32, permitting the armatures 33 to move outwardly within the solenoids 32, 105 allowing the lever links 34 to swing outwardly on their pivots 35; this moving of lever links outwardly on their pivots 35 will permit their wedged heads 36 to also move outwardly, acting upon the gripping jaws 110 37 to cause their outer ends to grip or tightly clamp the auxiliary rails 38.

Each wedged head 36 is provided at its inner end with a rod-like extension 39 of less size than the body of the head, and between the body of the head and the casing 40, positioned upon the rod-like extension 39, is a coil spring 41; this coil spring acts to force the head outwardly between the inner ends of the curved gripping jaws, when the magnet coil is deenergized. On 10 the body of each wedged head is a pin 42 that is positioned directly behind the lever link so that when the lever link, at its outer end, is pulled inwardly by reason of a current passing through the magnet 15 coil, this pulling of the outer end of lever link will cause the wedged head to move inwardly against the coil spring 41, permitting the rollers 43 on the inner end of the curved gripping jaws to travel on the head, 20 allowing the outer ends of the gripping jaws to release the rail 38 and permit the car to ascend and descend freely. In the head 36 is an elongated slot 44, and in this slot 44 is a pin 45 that assists in guiding the 25 head in its travel. A pin 42^a is positioned on each head in front of the lever link, to keep the lever link in perfect, assembled position. The hollow casing 40 is grooved on its outer face, and caps 46 bear in these 30 grooves and are held in place by bolts 47; the inner ends of the rod-like extensions 39 of the wedged heads work in the hollow guiding casing 40.

In Fig. 4, I have shown a diagram of the 35 wiring, in which 48 is the battery from which extends the wire 49 that leads to the magnet 19; thence wire 50 leads to one of the terminals 16 that carries the long blade 18, and thence through the short blade to 40 wire 51 that returns to one of the poles on the battery 48. Upon the car accidentally falling or traveling too fast, as hereinbefore explained, the governor breaks the circuit through blades 17 and 18, deenergizing the 45 magnet 19, and causing the weighted arm to fall and open the switch 30, which likewise deenergizes the magnet coil 32, thereby operating the clutch mechanism to cause the jaws thereof to tightly grip the auxiliary 50 rails 38 and stop the car. The wire 51 leads from the battery 48 to switch 30, and wire 52 leads from switch 30 to the magnet coil, and wire 53 leads from the magnet coil to the battery so that a complete circuit is created through these wires and elements when the switch 30 is closed, until the weight 55 falls upon the head 25 of switch 30, opening the switch and breaking the circuit.

While we have described the preferred 60 form of our safety apparatus for elevators, certain minor alterations or changes may be found necessary in the extensive manufacture of our apparatus, and, therefore, we reserve the right to make such minor alterations or changes as shall appear to one

skilled in the art to which this invention relates, which minor alterations or changes fairly fall within the scope of the appended claims.

What we claim is:

1. In an apparatus of the class described, the combination with a car and with a primary and auxiliary rails, of a governor-controlled switch carried by said car, a primary roller, means coöperating with the primary roller and the governor-controlled switch for operating the same when the car descends too rapidly, a magnet electrically connected to said governor-controlled switch, weighted means coöperating with said magnet and being held in a set position while the magnet is energized, a second switch carried by the car and provided with an angle-headed arm in the path of movement of the weighted means, and clutch means carried by the car and adapted to grip or act upon the auxiliary rails when the second switch is opened by the weighted means being released by the magnet and striking the head- 85 ed arm of the second switch. 90

2. In an apparatus of the class described, the combination with a car, of a clutch mechanism secured to the bottom of the car, said clutch mechanism comprising a pair of gripping jaw devices at each end of the car, each device provided with curved jaws, slotted wedged heads between the inner ends of each of the jaws of each jaw device, a grooved, hollow casing between the wedged heads, each head provided with a rod-like extension extending into the casing, a coil spring on the rod-like extension of each jaw between the body of the jaw and one end of the casing, caps resting in the groove of the casing, bolts extending through the caps and fastening the caps against the casing, lever links pivotally mounted at their inner ends upon the car and extending across the wedged heads, pins on the heads at opposite sides of each link, pins in the slots of the 110 heads for guiding the heads in their travel between the jaws of the jaw devices, and electrically-controlled means between the outer ends of the lever links for drawing the outer ends together and thereby leaving the jaw 115 devices free, or releasing the outer ends of the lever links and causing the springs to act to force the wedged heads farther between the jaws of the jaw devices for causing the outer ends of the jaws to exert a gripping 120 action. 125

3. In an apparatus of the class described, the combination with the floor of an elevator, of a clutch mechanism carried by said floor and comprising a pair of jaw devices, each jaw device including a pair of jaws, spring-pressed wedged heads positioned between the inner ends of the jaws, lever links extending across the heads, means on the heads whereby, when the lever links are 130

swung upon their pivots or fulcrums, the heads will be drawn inwardly for releasing the jaws of the jaw devices, a solenoid between the outer ends of the lever links, and 5 armatures in the solenoid and connected to the outer ends of the lever links whereby, while a current is passing through the solenoid, the lever links will be holding the wedged heads in an inoperative position, 10 but when the circuit is broken through the

solenoid, the lever links will be released to permit the wedged heads to spread the inner ends of the gripping jaws apart, causing the outer ends of the gripping jaws to exert a powerful gripping action.

15

In testimony whereof we hereunto affix our signatures.

GEORGE P. BARKER.
OLIVER E. UNDERWOOD.
